UNITED STATES PATENT OFFICE.

CLAUDE L. BEEARS AND JOSEPH HABART, OF CLEVELAND, OHIO, ASSIGNORS TO THE BANKERS SAVINGS & CREDIT SYSTEM COMPANY, OF CLEVELAND, OHIO, A CORPORATION OF OHIO.

COIN BANK.

Application filed March 20, 1924. Serial No. 700,493.

This invention relates to improvements in the construction of coin banks or receptacles, and more particularly to an improved coin slot protector for use in connection with such devices.

The primary purpose of the invention is to improve and at the same time simplify the construction and lessen the cost of production of coin banks or receptacles.

More specific objects are to provide a highly efficient coin slot protector that is very simple of construction; that is economical of production; that is convenient of assembly; that is durable; that is immune from disorder and therefore thoroughly reliable; and, in its preferred form, is constructed exclusively of die stamped sheet metal parts which interengage with each other in such manner as to make unnecessary the use of fastening means for connecting the parts together.

A further object is to provide common means for securing a bail or handle to the exterior, and the coin slot protector to the interior, of the receptacle, said means serving to hold the various elements against disarrangement.

The foregoing objects, with others herein-after appearing are attained in the construction illustrated in the accompanying drawing wherein Fig. 1 is a perspective view of a coin bank or receptacle incorporating our invention; Fig. 2 is a similar view of the coin slot protector with parts broken away to reveal certain structural details; Fig. 3 is a horizontal section through the bank or receptacle on the line 3—3 of Fig. 4 and looking upwardly as indicated by the arrows associated with said line; Fig. 4 is a longitudinal section through the upper portion of the receptacles; Figs. 5 and 6 are transverse sections through the receptacle on the line 5—5 of Fig. 4, the former view showing the receptacle in upright or normal position and the latter view showing it as inverted with the shutters of the coin slot protector in one of the positions which they might assume when the receptacle is inverted; Fig. 7 shows the two shutters in profile and arranged one above the other but in the same relative longitudinal positions which they occupy in the protector; and Fig. 8 is a sectional detail on the correspondingly numbered line of Fig. 4.

In the present embodiment of the invention, the coin bank or receptacle comprises

a shell or casing 1 that is preferably drawn from a single piece of sheet metal to provide a top 2 and a peripheral wall 3. A suitable closure (not shown) may be detachably connected to the open bottom of the receptacle in any approved manner, this feature constituting no part of our present invention. A coin slot 5 occupies the central portion of the top 2.

The coin slot protector comprises a housing that is preferably formed from a single piece of sheet metal and comprises a bottom wall 6, end walls 7, and side walls 8. Integral lugs 9 extend outwardly from the upper edges of the end walls 7 and their upper surfaces are substantially flush with the top edges of the walls 7 and 8. The wall 6 has a coin slot 10 which is in alignment with the coin slot 5 when the protector is properly suspended from the top 2.

Identical interchangeable shutters 12 are pivotally supported within the housing by the engagement of trunnions 13, which extend from the ends of the shutters adjacent their upper edges, within openings 14 that are formed in the end walls 7. The shutters are provided at the middle portion of their lower edges with series of teeth 15 which are offset from the longitudinal centers of the shutters substantially half the width of a tooth so that when the shutters are reversed with respect to each other the teeth of one are staggered with respect to those of the other, the shutters being arranged in this manner when placed within the housing. This offset arrangement of the teeth is clearly illustrated in Fig. 7.

A bail or handle 17 is shown as hingedly connected to the top 2 of the receptacle 1 by fastening means 18 which are formed to provide eyes within which the ends of the bail or handle 17 are journaled, and to provide legs which are extended through suitably shaped apertures in the top 2 and through registering slots 20 in the ears 9 beyond which said legs 19 are spread outwardly to hold the parts together, as best illustrated in Fig. 8.

When the receptacle is in upright position the shutters 12 hang in the position shown in Fig. 5, but when the receptacle is inverted, as illustrated in Fig. 6, the shutters fall together and may assume the position illustrated in said view. In this connection it may be explained that portions, designated 12^a, of the inner edges of the shutters, are ex-

tended an appreciable distance beyond the pivotal axes of the shutters and by contact of these portions with the side walls of the housing the shutters are prevented from 5 swinging beyond a predetermined distance inwardly as otherwise the shutters would be capable of swinging so far inwardly that they might lock in inoperative condition. It will be noted from Fig. 6 that the inner edges 10 of the shutters engage the side walls of the housing to prevent the outer edges of the shutters from swinging far enough toward the slotted wall of the casing to go beyond the common plane of the axes of the two 15 shutters. When the shutters occupy the position shown in Fig. 6, or any other possible of attainment within the housing when the receptacle is inverted, they obstruct the passageway between the coin slots 5 and 10 and 20 effectively prevent the dislodgment of a coin from the receptacle.

Having thus described our invention, what we claim is:

1. A coin bank comprising a receptacle 25 having a coin slot in its top, a housing secured to the inner side of the top, said housing comprising end walls, a bottom and side walls, the latter diverging upwardly from the bottom, the bottom having a coin slot 30 that is substantially in alignment with the coin slot of the top, and shutters having trunnions at their ends adjacent their upper edges while portions of said edges are extended an appreciable distance beyond the 35 axes of the trunnions, the end walls of the housing having apertures wherein said trun-

nions are journaled, the side walls of the housing limiting the outward movement of the upper and lower edges of the shutters thereby to prevent them from overbalancing 40 outwardly or swinging beyond a predetermined distance inwardly so that upon the inversion of the receptacle said shutters will swing inwardly by gravity a limited distance 45 and obstruct the coin passageway between said slots.

2. A coin bank comprising a receptacle having a coin slot in its top, a housing secured to the inner side of the top and comprising end walls, a bottom, and side walls, 50 the latter walls diverging upwardly from the bottom, the bottom having a coin slot that is substantially in alignment with the coin slot of the top, identical and interchangeable shutters having trunnions at their ends 55 adjacent their upper edges, the end walls of the housing having apertures within which said trunnions are journaled thereby to pivotally suspend the shutters within the housing on opposite sides of the coin passageway, 60 the inner edges of the shutters having series of teeth that are offset from the longitudinal axes of the shutters substantially half the width of a tooth, the shutters being reversed with respect to each other so that the teeth 65 of one are staggered with respect to those of the other.

In testimony whereof, we hereunto affix our signatures.

CLAUDE L. BEEARS.
